(57) **CLAIM**

The ornamental design for a handle for a louvre gallery, as shown and described.

DESCRIPTION

FIG. 1 is a top perspective view of a handle for a louvre gallery showing the claimed design;

FIG. 2 is a left side view thereof;

FIG. 3 is a top plan view thereof;

FIG. 4 is a right side view thereof; and,

FIG. 5 is a front view thereof.

The claim is shown with a symbolic break in its length. The appearance of any portion of the article between the break lines forms no part of the claimed design.
